No. 969.

Benjamin W. Dunklee's Design for a Stove.

Patented Dec. 15, 1857

Fig. 2.

Fig. 1.

UNITED STATES PATENT OFFICE.

B. W. DUNKLEE, OF BOSTON, MASSACHUSETTS.

DESIGN FOR A STOVE.

Specification forming part of Design No. 969, dated December 15, 1857.

To all whom it may concern:

Be it known that I, BENJAMIN W. DUNKLEE, of Boston, in the county of Suffolk and State of Massachusetts, have invented or produced a new and ornamental Design for a Parlor-Stove; and I do hereby declare that the same is fully represented in the accompanying drawings, of which—

Figure 1 is a perspective view in elevation of a stove constructed in accordance with such design; Fig. 2, a vertical section of the front portion of its water-urn, cap, base, front plate, and fire-pot, and ash-pit doors.

I do not intend to include in the said design any of the letters or figures shown thereon, but confine the said design to the aggregation of ornaments and moldings as exhibited, the same being shown in the drawings with suffi-

cient clearness to enable any pattern-maker of ordinary skill to produce the design in question.

In the said drawings, A represents the base of the stove; B, the ash-pit door; C, the front plate; D, the fire-place door; E, the cap-plate, and F the water-urn, the general form of the stove in horizontal section being oval, or approximately so.

I claim—

The design substantially as represented in the aforesaid drawings.

In testimony whereof I have hereunto set my signature this 31st day of July, A. D. 1857.

B. W. DUNKLEE.
